CLOSURE FOR COLLAPSIBLE TUBE, HAVING
A SPRING BIASED, AXIALLY RECIPRO-
CABLE, PRESSURE OPERATED OUTLET
VALVE

Samuel J. Jarvis, Pittsburgh, Pa.

Application September 22, 1949, Serial No. 117,118

1 Claim. (Cl. 222—496)

1

This invention relates to closures, more particularly to valved closures for collapsible containers and the like, for example, those generally used for tooth pastes, shaving creams, cosmetic creams, ointments, etc., and has for an object to provide improved apparatus of this character.

Another object of the invention is to provide a closure for containers of the type indicated which may be made as a unit separate from the container and adapted to be applied to any well-known form of collapsible container by the ultimate user thereof.

Yet another object of the invention is to provide a closure for collapsible containers which closure may be assembled as a permanent part of the container.

A further object of the invention is to provide a closure for collapsible containers or the like which will automatically open for delivery of the container contents upon application of pressure to the container, and which will automatically close upon release of such pressure.

These and other objects are effected by the invention as will be apparent from the following description and claims taken in connection with the accompanying drawings, forming a part of this application, in which:

Fig. 1 is a fragmentary perspective view of a collapsible container incorporating features of the present invention;

Fig. 2 is an enlarged fragmentary sectional view through the discharge end of a collapsible container such as shown in Fig. 1, with the closure device permanently secured to the container;

Fig. 3 is an exploded perspective view of the closure device;

Fig. 4 is a sectional view, similar to Fig. 2, but showing a modified construction of closure adapted to be removably applied to a conventional collapsible container; and,

Fig. 5 is a perspective view of the closure of Fig. 4.

Referring now to the drawing in more detail, the reference character 10 indicates a collapsible container, for example, a toothpaste tube, having the usual thin-walled cylindrical body 11 and domed end wall 12, the latter having a central opening 13 provided with a strengthening flange 14.

Where the tube end 12 and flange 14 are made of aluminum or other equally hard material, the closure device may be permanently attached to the container by press fitting, and a closure de-

2

vice for this type of attachment is shown in Figs. 1, 2 and 3 and comprises a neck member 16 whose outside diameter is a few thousandths of an inch greater at the innermost end than at the outer end to provide for a press fit assembly in the opening 13 of the container flange 14.

The neck member 16 has a longitudinal discharge passage 17 of circular cross section extending therethrough from end to end, terminating in a circular delivery opening 18 provided with an outwardly-facing frusto-conical valve seat 19.

Associated with the valve seat 19 is a conical valve member 21, preferably provided with an eye 22 at its apex for reception of a hook 23 formed at the outer end of a cylindrical helical tension spring 24 of a diameter to be closely received in the cylindrical passage 17. The innermost terminal coil 26 of the spring 24 is of greater diameter than the passage 17 and abuts a shoulder 27 at the inner end of the neck member 16. The length and resiliency of the spring is such that it exerts sufficient force on the valve member 21 to retain the latter in contact with the valve seat 19, thereby closing the delivery opening 18, except when pressure is applied to the collapsible container 10.

When pressure is applied to the collapsible container the valve member will be forced off its seat, permitting discharge of the contents of the container through the delivery opening 18. It will be seen that the use of a spring of the structure disclosed provides a substantially unobstructed passage therethrough for movement of the container contents to the delivery opening. Preferably, the spring is made of stainless steel so that it will resist corrosion from contact with the container contents.

While various angles for the inclined surfaces of the conical valve member 21 and seat 19 may be utilized, it has been found that an included angle within the range of from 74 degrees to 84 degrees produces especially satisfactory operation. Preferably, the included angle of the valve seat is one or two degrees greater than that of the valve with the result that the valve and seat have line contact.

In Figs. 4 and 5 there is illustrated a modified construction of closure adapted for removable attachment to any conventional type of collapsible closure 10a. In this construction, the container side walls 11a are closed at the outlet end by a domed wall 12a having a central opening 13a surrounded by a flange 14a which is externally

threaded, as at 15 for reception of the closure assembly 25.

This closure assembly includes a neck portion 16a having a cylindrical passage 17a terminating in a delivery opening 18a and surrounded by an outwardly-facing valve seat 19a, all as in the previously-disclosed construction. However, the neck member 16a is provided at its inner end with a relatively heavy flange 20 which is internally-threaded, as at 30, for attachment to the threaded flange 14a of the container. Also, the periphery of the flange 20 may be flattened, as at 35; for ease in manual application and removal of the closure unit.

The valve and spring construction and operation are identical in both forms of the invention shown, the form of Figs. 4 and 5 having a shoulder 27a at the inner end of the neck member 16a for support of the spring terminal coil 26.

From the above description it will be apparent that the invention provides an automatic closure which is simple in construction, yet effective in operation, and particularly one in which a substantially free passage is provided for movement of the container contents therewith to the delivery opening.

While the invention has been shown in but two forms, it will be apparent that it is not so limited, but is susceptible of various changes and modifications without departing from the spirit thereof.

What I claim is:

A closure member for a collapsible dispensing tube, comprising a neck member having a longitudinal discharge passage of circular cross section terminating in a circular delivery opening, an

outwardly-facing valve seat surrounding said delivery opening, a valve member associated with said valve seat, a shoulder at the inner end of the neck member and lying in a plane normal to the longitudinal axis of the neck discharge passage, and a cylindrical helical tension spring disposed in said passage in close proximity to the wall of the latter, the innermost terminal coil of said spring being of greater diameter than said passage and abutting said shoulder, and said spring terminating at its outer end in a diametrically-extending hook portion secured to the valve member, said spring construction and arrangement providing a substantially free passageway axially of the spring for unobstructed flow of material through the neck member to the delivery opening.
